United States Patent Office.

HERMANN VASSEUR, OF WALLINGFORD, CONNECTICUT, ASSIGNOR TO SIMPSON, HALL, MILLER & CO., OF SAME PLACE.

Design No. 3,754, dated November 16, 1869.

DESIGN FOR A TEA-SERVICE.

The Schedule referred to in these Letters Patent and making part of the same.

To all whom it may concern:

Be it known that I, HERMANN VASSEUR, of Wallingford, in the county of New Haven, and State of Connecticut, have invented a new Design for Tea-Service; and I do hereby declare the following, when taken in connection with the accompanying illustration, to be a full, clear, and exact description of the same, and which said illustration constitutes part of this specification, and represents a side view of the eleven pieces which compose the complete tea-service.

This invention relates to a design for tea-service, and consists in the general outline of the several pieces, and configuration or ornamentation of the same.

As here represented, the service is composed of eleven pieces. The same characteristic features are found in all the pieces, that is to say, the convex bottom below a plain band, conically-shaped body, draw-

ing into a neck, which from the union with the body upward, flares or opens. The legs which support the several pieces all correspond to each other, as also the ornamentation of the body. The handles, spouts, and other corresponding parts are as near like one to the other as the nature of the piece will admit, and all as fully shown in the accompanying photographic illustration.

I do not wish to be understood as confining my design to require any number of pieces, either one of several pieces containing in itself the design which I desire to secure by Letters Patent.

I claim, as my invention—

The design for tea-service, as described and shown.

HERMANN VASSEUR.
